Nathaniel Chapman, of Pen-y-ank, State of New York.

Letter Patent.

The schedule appears to in these Letters Patent and making part of the same, containing a description in the words of the said Nathaniel Chapman himself of his improvement in the forcing pump.

To all to whom these presents shall come: Be it known, that I, Nathaniel Chapman, of Pen-y-ank, in the County of Ulster, State of New York, have invented and made useful improvement in the manufacturing and use of forcing pumps, for drawing water, for the purpose of a fire engine and for domestic uses, and that the following is a full and exact description of the construction and operation of the said machine, as invented or improved by me: The figure exhibits a view of the improvement of the double forcing pump, designed for the purpose of a fire engine, and for domestic uses, and is so proportionately made as to prevent a section. The figure represents the barrel A. and B. with the piston C and D, in them, where are made by the lever E directly above whose fulcrum is at E, and they are both in motion at the same time, C upwards and D downwards, and by the tendency to form a vacuum beneath the ascending piston the water is drawn in through the suction pipe F. and opens the valve R, to supply the vacuum in the barrel A. formed by the motion of the piston C. By this simple motion of the pump it may be seen that the piston of the descending piston D, has closed the valve R, in the bottom of the barrel B, to prevent the return of the water whence it comes, and against the valve S, which is an aperture in the form of a V. between the barrels, during its descending, of this discharging orifice P. E. one

at a time, it being necessary to close upon one of the instant of valves from the stem to prevent a current between the barrels, and giving the depressurized water a free passage through the connection pipe & into the receiver T , which surrounds the top of both barrels, & serves to regulate the current of water by the admittance and escape of air through the forcing pipe H , as it is discharged through the siphon J . This regulating would be produced by discharging the barrels several at a time. Q. appears an air pocket which is connected with the receiver T , and is only used when the siphon J is stopped for the purpose of sending water through the pipe H , in an upper vessel, or by the addition of the direction pipe, C, for the forcing pipe H . This acts upon the water when passing through the pipe H , and keeps it in regular and uniform motion, & the machine is fastened upon its base M by means of thumb bolts, I , passing through an iron collar, I . I , which surrounds the bottom of the barrels, which rest upon a flange at the division of the barrels from their base, at M , & supports the base which encloses the machinery, and is fastened to the base by bolts.

The use and principle of working it is believed to be efficient, as planned in the foregoing description, and it may be applied to any barrel for drawing water from a well or cistern, or liquid from any vessel, and by stopping tightly the siphon J may serve to draw water into an upper vessel or at any time by means of the direction pipe, C. It is cheap construction and simple, and its construction has no part of it necessary understanding, being liable to a poor man's capacity, or to a man's obtuseness of judgment without applying to a professor of mechanics. The construction and improvement on the principle forcing pipe, may be used for which a patent is claimed. The construction of the valve H , which has a double elevation in passing to stop the original $P.P.$, one at a time, out of the piston D , in the barrel B is according to

stops the orifice D in the barrel A, and vice versa, in the pump we common use two valves are required to stop the orifice D. In fitting the valves R, R, without making being a part of the leather in the division, and in fitting the pump together with bolt, and fastening it down well an iron collar so that any one may take it apart and put it together again with ease in the old pump it was all fastened together so that it required a mallet of pump to take it apart again it was just it together again. 3. In surrounding this type of the barrels A, B with the reservoir D, In the old pump in use the reservoir was placed between the bottoms of the barrels, and always left water stand so that it was never dry, but always wet & uncomfortable. By this improvement the reservoir is always emptied when the requisite quantity of water has been drawn. 4. In constructing this case at A, so that it may be taken off, whole by any one for the purpose of repairing or cleaning the pump machinery. 5. The suction pipe E being divided like a V so as to supply through a different orifice either barrel and thus suffering from the old pump which had but one orifice to supply both barrels B. In adding the connecting pipe G and comes to a point at the base. In the former pump the two barrels were placed some distance apart and had no pipe like G. This is so constructed as to join with both barrels, and may be cast at the same time. 6. An improvement in adapting an old pump to various purposes. The principle of the forcing pipe H, and direction pipe G, acting as an engine apart by means of the machinery of a forcing pump, is not claimed to be an invention but an improvement in applying that principle to a pump for domestic purposes, which it is believed has never before been done, also in adding to the pump the air valve Q, which regulates the stream or jet of water and makes it while the receiver is supplied steady and constant. The double forcing pump in common use has neither the pipes H.

or O, nor the air before G, but is implied as to the purpose of drawing water through a siphon like I. The Engine pump may be made on a small scale, and from the nature of its construction, of the most durable materials, and will occupy a very small place in a kitchen.

In testimony that the within is a true specification of my said improvement as within described I have hereunto set my hand the forth day of March in the year of our Lord One thousand eight hundred and thirty six Nitropey

Henry A. Nitropey John L. Lewis, Notary H. A. Nitropey
